INVENTOR.

Theodore Parobi.

BY

Oscar Geier

HIS ATTORNEY.

UNITED STATES PATENT OFFICE.

THEODORE PAROBI, OF DUNDEE LAKE, NEW JERSEY.

SHOE.

1,269,737.

Specification of Letters Patent. Patented June 18, 1918.

Application filed July 27, 1917. Serial No. 183,057.

To all whom it may concern:

Be it known that I, THEODORE PAROBI, a subject of the Emperor of Austria, and a resident of Dundee Lake, county of Bergen, 5 and State of New Jersey, have invented certain new and useful Improvements in Shoes, of which the following is a specification.

This invention relates to improvements in shoes, and has as its special object the provision of means whereby water or moisture is prevented from entering the interior of the shoe, the same being rendered thoroughly waterproof by the construction described.

A further object is to provide such means 15 in a form which presents no peculiar or objectionable appearance.

This invention is particularly useful to people obliged to walk or stand in snow or mud, the moisture soon serving to saturate 20 the material of which shoes are usually constructed, thereby rendering the foot of the wearer uncomfortable and causing him to be liable to colds and more serious complications arising therefrom. At the same time, 25 the use of the invention dispenses with the necessity of wearing of rubbers, overshoes or other exterior foot covering.

These and other like objects are attained 30 by the novel construction and combination of parts hereafter described and shown in the accompanying drawing, forming a material part of this disclosure, and in which—

Figure 1 is a vertical sectional view, taken through the longitudinal center, of a 35 shoe made in accordance with the invention.

Fig. 2 is a transverse vertical view taken on line 2—2 of Fig. 1.

The shoe indicated by the numeral 10 may be made in any conventional design 10 or type desired, the peculiar construction employed, however, having an inner lining 14, of soft pliable leather, the same extending over the innersole and up upon the upper of the shoe as indicated. The shoe consists, it will be noted, of the overlapping 15 upper and lower sections designated respectively 1 and 2, which are secured together midway of the shoe. It will be observed that the waterproof filler sole 15 extends up 20 upon the upper to the connection between the upper and lower parts thereof.

The welt sole 16 of the shoe 10 is attached in the ordinary manner, while immediately above and below are fillers 15 and 17, to which the outer sole 18 is applied, while the 55 heel 19, comprised of a plurality of lifts, is attached in the usual manner.

Both filler soles 15 and 17 are made of an impervious substance, preferably the bladder of animals, such as a hog, the same 60 having been thoroughly impregnated with a composition consisting of shoe-maker's wax in the form of a black tarry pitch, fish or whale oil, and beef suet, all being melted and intimately commingled, in which composition the bladders are boiled so as to be thoroughly saturated, and in which condition they are cut and used as indicated, the composition rendering them absolutely 65 waterproof. 70

From the foregoing, it will be seen that a waterproof shoe has been disclosed, which has the same appearance as an ordinary shoe, and which can be constructed at substantially the same cost, furthermore that 75 the shoe will be as flexible and easy to wear as that made by ordinary processes.

Having thus described my invention what I claim as new and desire to secure by Letters Patent, is— 80

A shoe consisting of an upper section and a lower section of leather, the lower section overlapping the upper section midway of the shoe, the overlapping portions of both sections being secured together, an inner sole to which the lower shoe section is secured, a moisture-proof lining having its opposite end edges projecting in line with the edges of the upper section and overlying said inner sole, a leather lining overlying the inner face of the lower section and upper section as well as said moisture-proof lining, and a similar moisture-proof lining as the first-moisture-proof lining placed between said inner sole and an outer sole 90 95 attached thereto.

In testimony whereof I have affixed my signature.

THEODORE PAROBI.
